UNITED STATES PATENT OFFICE.

ALBERT B. NORWALK, OF NEW YORK, N. Y.

DESIGN FOR A DOLL.

53,084.

Specification for Design.

Patented Mar. 11, 1919

Application filed November 15, 1918. Serial No. 262,726. Term of patent 14 years.

To all whom it may concern:

Be it known that I, ALBERT B. NORWALK, a citizen of the United States, residing in the borough of Manhattan, in the city of New York, county of New York, and State of New York, have invented a new, original, and ornamental Design for Dolls, of which the following is a specification, reference being had to the accompanying drawing, forming part thereof.

The figure is a perspective view of a doll showing my new design.

I claim:

The ornamental design for a doll, as shown.

ALBERT B. NORWALK.
